UNITED STATES PATENT OFFICE

HENRY C. HERR, OF BUFFALO, NEW YORK, ASSIGNOR TO HERR MANUFACTURING CO. INC., OF BUFFALO, NEW YORK, A CORPORATION OF NEW YORK

SELF-LUBRICATING SPINNING RING

Application filed November 25, 1929. Serial No. 409,453.

This invention relates to improvements in the spinning rings of spinning machines on which the thread guides or travelers are mounted, and particularly to a spinning ring which is self-lubricating.

One of its objects is the provision of a self-lubricating ring of this character which is so designed as to prevent the lubricant deposited on the bearing face of the ring being thrown or sprayed outwardly onto adjoining bobbins and soiling the threads.

Another object of the invention is to provide a spinning ring having means for effectively and uniformly distributing the lubricant over its bearing surfaces.

In the accompanying drawing:

Figure 1 is a fragmentary sectional side view of a spinning machine showing the traverse or guide ring and associated parts. Figure 2 is an enlarged top plan view of the improved ring and its holder with the bar traveler in position thereon. Figure 3 is an enlarged transverse section on line 3-3, Figure 2. Figure 4 is a bottom plan view of the spinning ring. Figure 5 is an enlarged fragmentary cross-section of the ring in the plane of line 5-5, Figure 4.

Similar characters of reference indicate corresponding parts throughout the several views.

Referring now to Figure 1 showing a part of a spinning machine of ordinary construction, 10 indicates the take-up spool applied to the revolving spindle 11 driven by the belt 12 engaging the spool-pulley 13. In machines of this character, there is a set of feed rolls for the threads to be twisted and a take-up spool for each vertical row of supply bobbins and traversing the several take-up spools from end to end thereof is a vertically-reciprocating bar 14, each spool extending through a corresponding opening 15 in the bar. Mounted on the top of the latter and surrounding the companion take-up spool 10 is a traverse ring 16 upon which the bar traveler 17 is adapted to revolve. During the operation of the machine, the bar traveler assumes a substantially upright position and revolves with and about the take-up spool, the threads passing under the trav-

eler before being wound upon the spool, and the traverse bar being reciprocated so that the threads are uniformly wound upon the spool in layers. As shown in Figures 2 and 3, the traverse ring 16 is removably seated 55 on yieldable brackets 18 rising from a base-ring 19 suitably fastened to the reciprocating bar 14. The inner edge of the base-ring terminates in an upwardly-facing annular flange 20 which is spaced from the inner edge of the traverse ring to produce an annular channel 21 for receiving the depending legs of the bar traveler. The lower side of the traverse ring is spaced from the top of the base-ring 19 to produce a lateral 60 continuation of the bar traveler receiving channel and such side is slightly flared or beveled upwardly and outwardly, providing a bearing face for the bar traveler.

For the purpose of effectually lubricating 70 the bar traveler, I make the traverse ring 16 of a hollow structure to provide a self-contained lubricant chamber 22, within its ordinary dimensional lines, having a restricted passage 23 at its inner edge or wall for supplying the necessary amount of lubricant to such inner edge and thence to the bar traveler, the lubricant flowing by gravity and aided by centrifugal force to the lower free 75 ends of said traveler which engages the lower 80 bearing face of the traverse ring. In the preferred embodiment of the invention shown in the drawing, the ring is composed of a lower or base section 24 having an annular groove 25 which forms the body of the 85 lubricant chamber, and an upper or cover section 26 which is shaped to extend over the grooved upper side of the base ring and around the outer side wall of the latter, such parts being united to constitute a unitary 90 structure by a pressed fit or otherwise. The inner edge of the top wall of the cover section 26 is preferably turned downwardly to form a flange 27 which produces a smooth, finished surface. The inner wall 28 of the 95 grooved ring-section 24 is preferably convexly curved at its inner edge and it slightly overlaps the flange 27 of the cover section in spaced relation to produce the restricted 100 passage 23 for the emission or delivery of

the lubricant directly on to the curved face of said wall 28 and below the top wall of the cover section, as seen clearly in Figures 3 and 5. It will be observed in these figures that the top surface of the cover section 26 is slightly inclined downwardly and inwardly and that the lubricant-passage 23 of the ring is below the level of the outer top side of the lubricant chamber 22, resulting in a gravity feed of the lubricant from said chamber through its restricted passage. However, the head pressure on the lubricant is not sufficient to force it freely through the passage 23, due to the adhesion of the lubricant to the passage-walls, and the lubricant forms in a thin film or fillet at the meeting edges of the ring parts 27, 28. As the traveler revolves about the traverse ring, it picks up sufficient oil to constantly and thoroughly lubricate the lower bearing surface of the ring, the oil flowing down the legs of the traveler and thence outwardly by centrifugal force where it deposits a film of oil on said bearing surface.

In its top side the cover section 26 of the traverse ring has one or more vents 30 which serve not only to eliminate the formation of air pockets in the lubricant-chamber 22 but also serve as inlets for introducing the lubricant thereto. These vents are preferably formed with rims or collars 31 projecting above the surface of the ring-cover which act to avoid overflowing of the lubricant-chamber.

In order to retain the lubricant on the undersurface or bearing side of the traverse ring where it is required to effectually lubricate the bar traveler, and to eliminate the spraying of any surplus oil or lubricant onto adjoining bobbins, I provide a guard rim or retaining member at the periphery of the ring. As clearly shown in Figures 3 and 5, this guard rim is in the form of a depending annular flange 32 which may be formed integrally with the cover-section 26 of the ring, being a continuation of its outer wall, and extends somewhat below the lower bearing side of the base section 24 of the ring, the lower edge of the flange terminating above the ring-holder 19 and resting on the brackets 18 thereof. By this construction, any surplus oil delivered to the underside of the ring is directed against the guard flange 32 and collects in the form of a fillet in the corner described by the adjoining faces of the ring and said guard flange. The consistency of the oil and its capillary attraction retains it in this manner and the lubricant has a tendency to flow downwardly and inwardly in a thin film on the lower inclined bearing side of the ring so as to effectually lubricate it.

In its underside or bottom wall the traverse ring has a comparatively small lubricant discharge port 33 which is preferably positioned adjacent to the depending guard

flange 32, where it is beyond the normal path of travel of the traveler bar legs, as seen in Figure 5. The lubricant discharged through this port assumes a small semi-globular form about the lower end of the port, the consistency of the oil and its capillary attraction producing this result. As the bar traveler traverses the ring, its legs dip into the puddle formed about the port and in so doing pick up some of the lubricant to lubricate it.

While the sections 24, 26 may be joined in any approved manner to form the hollow traverse ring, I prefer to hold these parts against displacement by inwardly facing projections 34 provided in the depending guard flange 32 and disposed to bear against the contiguous outer edge of the lower ring section 24, as seen in Figures 3 and 5.

I claim as my invention:

1. A device of the character described, comprising a traverse ring for a bar traveler containing a lubricant-chamber and formed of an upper section and a lower section having oppositely-facing flanges at the inner peripheries thereof, said flanges being spaced apart in overlapping substantially vertical relation to provide a lubricant discharge passage, and a depending guard rim applied to the outer edge of the upper section and extending below the bottom side of the lower section.

2. A device of the character described, comprising a hollow traverse ring containing a lubricant-chamber having a concentrically arranged lubricant discharge passage located substantially at the junction of the top wall and the inner wall of said ring, the top wall of said ring being inclined downwardly and inwardly to provide a gravity feed for the lubricant from its chamber through said discharge passage, and an annular guard flange applied to the outer periphery of said traverse ring and extending below the underside thereof.

3. A device of the character described, comprising a traverse ring for a bar traveler containing a lubricant-chamber having a discharge passage at the inner peripheral edge thereof and including a downwardly and inwardly inclined top wall and an upwardly and outwardly inclined bottom bearing wall onto which the lubricant is delivered, and a depending, annular guard flange extending from the outer edge of said top wall below the surface of said bearing wall.

4. A device of the character described, comprising a hollow traverse ring for a bar traveler adapted to contain a supply of lubricant and an annular restricted lubricant passage provided in the inner wall of the ring between its top and bottom walls, said passage opening upwardly and the lubricant being discharged onto said inner wall by the head pressure of the lubricant contained in said ring, a depending guard rim extending

around the outer edge of the traverse ring, and a port in the bottom wall of said ring for discharging lubricant thereon adjacent to the outer portion thereof, said port being located beyond the path of travel of the bar traveler.

5 5. A device of the character described, comprising a hollow traverse ring for a bar traveler adapted to contain a supply of lubricant, and an annular flange extending around the periphery of said ring and depending below its bottom bearing face, the latter having a lubricant-discharge port therein adjacent said flange.

10 6. A device of the character described, comprising a hollow traverse ring for a bar traveler adapted to contain a supply of lubricant, and an annular flange extending around the periphery of said ring and depending below its bottom bearing face, the latter having a lubricant-discharge port therein, said port being located at a point between said flange and the path of travel of the bearing end of the bar traveler.

15 7. A device of the character described, comprising a hollow traverse ring adapted to contain a supply of lubricant and having a bearing surface for a bar traveler on its bottom side and a lubricant-conducting passage for feeding the lubricant by gravity to such bearing surface, and a guard member extending around the periphery of the ring below its bearing surface.
